UNITED STATES PATENT OFFICE

GROVER CLEVELAND TUCKER, OF TUSCALOOSA, ALABAMA, ASSIGNOR TO TUCKER IMPLEMENT COMPANY, INC., OF GREENSBORO, ALABAMA, A CORPORATION OF ALABAMA.

INSECT-DESTROYER.

14,432.

Specification of Reissued Letters Patent. Reissued Feb. 12, 1918.

Original No. 1,189,508, dated July 4, 1916, Serial No. 67,235, filed December 16, 1915. Application for reissue filed April 28, 1917. Serial No. 165,273.

To all whom it may concern:

Be it known that I, GROVER C. TUCKER, a citizen of the United States, residing at Tuscaloosa, in the county of Tuscaloosa and

5 State of Alabama, have invented certain new and useful Improvements in Insect-Destroyers, of which the following is a specification, reference being had to the accompanying drawings.

10 This invention relates to certain improvements in insect destroyers and has relation more particularly to a device of this general character especially designed and adapted for use in connection with boll weevils, and it is an object of the invention to provide a device of this general character including means whereby a plant is effectively agitated to assure the release of the insects thereon.

15 Furthermore it is an object of the invention to provide a novel and improved device of this general character wherein a poisoning solution is employed and into which the insects disengaged from the plants are delivered.

20 It is also an object of the invention to provide a novel and improved insect destroyer wherein is employed containers for poisoning solutions positioned at opposite sides 80 of a row of plants and which are directed entirely below a plant before the agitating means is engaged with the plant, whereby the escape of a released insect is substantially eliminated.

25 The invention also contemplates for an object to provide a destroyer of this general character including a rotary beater comprising blades between which the foliage of a plant is directed to assure a proper agitation of the plant and whereby a blast of air is imposed upon the plant to further assure the removal of the insects lodged upon the plant.

30 The invention consists in the details of construction and in the combination and arrangement of the several parts of my improved insect destroyer whereby certain important advantages are attained and the device is rendered simpler, less expensive and 45 otherwise more convenient and advantageous for use, all as will be hereinafter more fully set forth.

The novel features of the invention will be carefully defined in the appended claims.

In order that my invention may be the 55 better understood, I will now proceed to describe the same with reference to the accompanying drawings, wherein—

Figure 1 is a view in top plan of an insect destroyer constructed in accordance 60 with an embodiment of my invention;

Fig. 2 is a longitudinal vertical sectional view taken through the device as shown in Fig. 1;

Fig. 3 is a view in front elevation of my 65 device as herein set forth;

Fig. 4 is a transverse sectional view taken on the line 4—4 of Fig. 2;

Fig. 5 is a fragmentary sectional view taken through the marginal portion of the 70 beater as herein set forth; and

Fig. 6 is a fragmentary view partly in elevation and partly in section, illustrating in detail a mounting for the beater shaft as herein included.

75 As disclosed in the accompanying drawings, 1 denotes an axle having fixed to the extremities thereof the traction wheels 2 of predetermined dimensions and loosely mounted upon the axle 1 intermediate the 80 wheels 2, is the body B.

As herein included, the body B comprises the side members 3 arranged on relative inclines and having their lower ends terminating in the upwardly and inwardly extending flanges 4 whereby the troughs T are afforded, and it is to be observed that the rear portions of the flanges 4 are connected to afford the arch 5, said arch being of such a height as to readily permit the plants to 90 pass therebeneath. It is to be understood that in use the sides 3 are adapted to be arranged on opposite sides of a row of plants as are also the troughs T.

The rear ends of the sides 3 and the arch 95 5 are connected by the back plate 6 and the side plates have also projecting rearwardly therefrom the handles 7 whereby the requisite rocking movement may be given to the body B as the requirements of practice may 100 require, and whereby the same may be readily guided in its travel.

Any conventional poisoning solution is adapted to be placed within the troughs T and in order to maintain said solution in a 105 state of quiescence, I intersect each of the troughs by the partitions 8, certain of said partitions forming a part of the transverse

brackets 9 for reinforcing the body B and serving to maintain the side members 3 in their operative relation. The top portions of the troughs T at the forward ends thereof 5 are provided with the plates 8^a overlying the same and which serve to prevent spilling of the solution within the troughs, and also as a guard to prevent the foliage of the plants from entering within the troughs and 10 forcing the solution therefrom.

The lower ends of the sides 3 have secured thereto the shoes 10 of suitable material and as the axle 1 is positioned adjacent the rear of the body B, it will be observed 15 that the forward portions of the shoes will engage upon the ground and thereby tend to guide the device in its travel, yet permitting a ready and convenient lateral adjustment so that a plant offset from the row 20 may be readily caused to pass between the troughs T.

It is to be observed that the free marginal portions of the flanges 4 are returned as at 11 to afford lips which positively assure the delivery of an insect, such as a boll 25 weevil, within the troughs and which also serve to prevent the solution within the troughs from splashing over the upper ends of the flanges 4 during the travel of the device.

Intermediate its length, the axle 1 has fixed thereto the beveled gear 12 which is in mesh with the beveled pinion 14 carried by the inner end of the shaft 15, disposed longitudinally of the body B and positioned intermediate the troughs T and as herein embodied, the inner end of the shaft 15 is supported by the bearing 16 carried by the yoke 17 loosely mounted upon the axle 1, while 40 the outer end portion of the shaft 15 is supported by the bearing 18 pivotally supported within the opening 19, formed in the vertically adjustable plate 20. By this arrangement it will be perceived that the outer or free end of the shaft 15 may be vertically adjusted in accordance with the requirements of practice.

The outer or free end of the shaft 15 has fixed thereto a beater comprising a hub 21 50 from which substantially radiate the substantially semi-circular and diametrically opposed blades 22, the hand of which is such as to afford substantially a spiral action and between which the foliage of the 55 plant is adapted to pass whereby it will be perceived that such foliage is thoroughly agitated which assures the disengagement of the insects from the plant. It is also to be noted that the adjacent ends of the blades 60 at their peripheral portions are in overlying relation whereby the action upon the foliage is materially increased. Furthermore it is to be observed that the rotation of the beater is such as to cause the foliage to move rearwardly which eliminates the possibility of 65

escape of any of the insects disengaged from the plant. Furthermore it will be observed that the hand of the blades 22 is such as to direct air blasts upon the foliage which further assures the release of the insects and 70 which also in practice has been found to prevent undue injury to the plant by the beater.

While I herein disclose the beater as serving to cause the foliage to move rearwardly, I do not wish to be understood as limiting 75 myself in this respect as the beater will operate with equal facility when the blades thereof are arranged to cause the foliage to move forwardly.

It is also particularly desirable to have 80 the free marginal portions of the blades of the beater beaded as indicated at 23, so that possibility of injury to the plant is further reduced.

It is to be particularly noted that the axle 85 1 is positioned rearwardly of the center of gravity of the device so that the handles 7 are relieved of the weight of the device during the working operation so that the operator is enabled to control the device with the 90 minimum of exertion. With the axle 1 positioned rearwardly of the center of gravity of the device, the weight of the device will be supported by the draft animal.

It is to be noted that the shaft 15 is of 95 such a length as to position the beater rearwardly of the forward ends of the troughs T and a distance sufficient to assure the forward ends of the troughs to be disposed beneath a plant before the same is operated 100 upon by the beater. This arrangement affords a further means whereby the escape of an insect is eliminated.

Each of the shoes 10 adjacent its forward end is provided with a laterally disposed 105 wing 24 affording a hitch whereby a draft rigging may be suitably engaged with the device and whereby the draft animal will be caused to travel between the rows of plants, it being self-evident that the line of travel 110 of the device proper may be readily controlled through the medium of the handles 7. By having the wing 24 positioned adjacent the forward end of the body and below the axle 1 it will be at once self evident 115 that the draft animal when hitched to the body serves to move the forward end portion of the body upwardly when the device is in transit and which, in practice, imparts a rocking movement to the 120 body B, with the result that the foliage of the plants is effectively agitated. This rocking movement of the body is assured in view of the fact that the device is drawn at a comparatively low rate of speed. This 125 rocking movement is further facilitated in view of the fact that the handles 7 are secured to the side members 3 adjacent the top thereof and above the axle 1.

It is to be noted that the cross sectional 130

configuration of the troughs T and the co-acting shoes 10 is substantially V-shaped and thus permits the device to be run through the ground to enable the troughs 5 to go under very low branches of the plants without injury thereto. In other words the bottoms of the troughs T present cutting edges which can readily penetrate the earth and thus position the receiving ends of the 10 troughs under the lower branches of the plants. It will also be noted that with the troughs T substantially V-shaped in cross section, the space therebetween is substantially in the form of an inverted V which 15 permits the machine to travel over earth clods or earth or stones which would otherwise impede its progress or unduly elevate the body B.

From the foregoing description, it is 20 thought to be obvious that an insect destroyer constructed in accordance with my invention is of an extremely simple and comparatively inexpensive nature and is particularly well adapted for use by reason 25 of the convenience and facility with which it may be assembled, and it will also be obvious that my invention is susceptible of some change and modification without material departure from the principles and 30 spirit thereof and for this reason I do not wish to be understood as limiting myself to the precise arrangement and formation of the several parts herein shown in carrying out my invention in practice.

35 I claim:

1. An insect destroyer comprising a portable body adapted to straddle a row of plants and provided with troughs between which the plants are adapted to pass, and 40 a beater rotating about an axis disposed longitudinally of the troughs and occupying a vertical plane intermediate the troughs, said beater including substantially spirally arranged and diametrically opposed 45 blades between which the foliage of the plant is adapted to travel, said blades serving to create air blasts, said blades being substantially semi-circular with the adjacent ends thereof at their peripheral portions 50 in overlying relation.

2. A device of the character described comprising a wheel supported axle, a body mounted for rocking movement upon said axle, the forward end of said body at its 55 bottom portion being provided with a trough, agitating means positioned above

the trough, hitching means carried by a side of the body adjacent the forward end thereof and in close proximity to the bottom thereof and at a point below the axis 60 of the body and handles disposed rearwardly from the body at the upper portion thereof, said handles being secured directly to the body rearwardly of and above the axis of the body, the axle being positioned 65 rearwardly of the center of gravity of the device whereby, during the working operation, the weight of the device is carried by the animal and the handles relieved therefrom. 70

3. An insect destroyer comprising a portable body provided with a trough and a beater rotatably supported by the body in a plane above the trough, said beater including substantially spirally arranged and 75 diametrically opposed blades between which the foliage of a plant is adapted to travel, said blades being substantially semicircular with the adjacent ends thereof at their peripheral portions in overlying relation. 80

4. A device of the character described comprising a body mounted for rocking movement, the forward end of said body at its bottom portion being provided with a trough, agitating means carried by the body, 85 and a shoe carried by the bottom of the body and adapted to penetrate the surface over which the body traverses.

5. A device of the character described including a portable body, said portable 90 body comprising downwardly and inwardly inclined sides provided at their lower margins with troughs substantially V shape in cross section, the forward end portions of the troughs being adapted to penetrate the 95 surface over which the frame traverses, and agitating means supported by the body and positioned above the troughs.

6. In an insect destroyer, a rotatable beater including substantially spirally arranged and diametrically opposed blades between which the foliage of a plant is adapted to travel, said blades being substantially semicircular with the adjacent ends thereof at their peripheral portions 105 in overlying relation.

In testimony whereof I hereunto affix my signature in the presence of two witnesses.

GROVER CLEVELAND TUCKER.
